CLAIM

The ornamental design for a top for table or desk as shown and described.

DESCRIPTION

FIG. 1 is a perspective view of a top for table or desk showing my new design, according to a first embodiment; FIG. 2 is a front elevational view thereof; FIG. 3 is a rear elevational view thereof; FIG. 4 is a right side elevational view thereof; FIG. 5 is a left side elevational view thereof; FIG. 6 is a top plan view thereof; FIG. 7 is a bottom plan view thereof; FIG. 8 is another perspective view similar to FIG. 1 but includes unclaimed environmental structure; FIG. 9 is a top plan view of the top for table or desk showing my new design according to a second embodiment, the second embodiment being identical to the first embodiment except that the top for table or desk according to the second embodiment is shown broken away; FIG. 10 is a top plan view of the top for table or desk showing my new design according to a third embodiment, the third embodiment being identical to the first embodiment except that the top for table or desk according to the third embodiment is shown broken away; and, FIG. 11 is a top plan view of the top for table or desk showing my new design according to a fourth embodiment, the fourth embodiment being identical to the first embodiment except that the top for table or desk according to the fourth embodiment is shown broken away.

The broken lines of equal dash length in each of FIGS. 1 and 6-11 show portions of the top for table or desk that form no part of the claimed design.

The areas encircled by the broken lines of equal dash length in FIGS. 1 and 6-11 show unclaimed areas of the top for table or desk that form no part of the claimed design.

The long dash-short dash-short dash broken lines in FIG. 8 show unclaimed environmental structure and form no part of the claimed design.

In FIG. 9, the top for table or desk according to the second embodiment is shown with a symbolic break. The appearance of any portion of the top for table or desk between the break lines forms no part of the claimed design.

In FIG. 10, the top for table or desk according to the third embodiment is shown with a symbolic break. The appearance of any portion of the top for table or desk between the break lines forms no part of the claimed design.

In FIG. 11, the top for table or desk according to the fourth embodiment is shown with symbolic breaks. The appearance of any portion of the top for table or desk between the break lines forms no part of the claimed design.
